UNITED STATES PATENT OFFICE

HAROLD W. SHONNARD, OF MONTCLAIR, NEW JERSEY, ASSIGNOR TO ELEVATOR SUPPLIES COMPANY, A CORPORATION OF NEW JERSEY

OPERATING MEANS FOR ELEVATOR DOORS

Application filed September 27, 1926. Serial No. 137,939.

The present invention relates to an improved form of solenoid operated cam of the type commonly used on elevators for operation of the doors at the various floors.

5 One of the objects of the present invention is to provide a device of the character named having relatively few parts, easily assembled and kept in order, and so constructed and arranged as to be at all times reliable in 10 operation.

Another object of this invention is provision of a valve operating cam of the general character described so constructed as to be normally moved into operative position 15 by mechanical or electro-mechanical means in such a manner as to be retarded during the latter part of the said movement.

Another object of the invention is to provide a device of the character named which 20 can be easily operated by hand or foot power in case any accident should interfere with normal operation by means of the solenoid.

The invention is illustrated in a preferred form in the accompanying drawings, wherein 25 Figure 1 is a view of my improved device shown principally in median longitudinal section, certain parts being shown in side elevation, Figure 2 is a transverse vertical sectional view of the same, and Figure 3 shows 30 the same in end elevation.

In the specific form of my invention herein shown and described, the motivating cam for the valve-operating devices on successive floors is operated by means of a solenoid 35 or equivalent electro-magnetic means. My broad invention, however, is not limited to actuating means of this character.

In the drawings herein, the usual valve operating cam is shown at 10, carried directly upon the end of a rod 11, which is fitted to slide easily within the sleeve 12.

The moving parts of my device are carried by a supporting casing 13, which preferably 45 takes the form of a casting so formed as to provide an oil chamber 14, and a guide 15 for the sleeve 12.

The supporting casing 13 also carries the bearing 16 for the stub shaft 17, upon which 50 shaft is fixed the gear 18. The sleeve 12 is

provided with teeth 19 forming a rack with which the gear 18 engages.

The supporting casing is also formed to provide a bearing 20, into which there fits a tube 21 closed at its two ends by plugs 22 55 and 23, and within which there slides a core 24 of soft iron or steel 24 provided with teeth 25 forming a rack which also engages with the teeth of the gear 18. To permit of this engagement, the tube 21 has an opening 26. 60 A second opening 27 in said tube communicates with the bottom of the oil chamber 14.

The core 24 has a central bore 28 with a branch opening 29 communicating with the bottom of the oil chamber (see Fig. 1). One 65 end of the bore 28 is permanently open as shown on the right in Figure 1, while the opposite end has a valve seat for a ball valve 30, which is prevented from falling out by the pin 31. 70

One end of the tube 21 and magnetic core 24 is surrounded by a solenoid core 32 which may be energized from a switch in the elevator car in a well known manner through the wires 33, 34. 75

The core 24, in addition to the bore 28 is provided with a supplemental bore 35, having a branch 36 communicating with the oil chamber 14 above the core 24 between two of the teeth of the rack 25 (see Fig. 1). 80

At the top of the casing 13 is an extension 37, which is bored to form a guide for the rod 38, one end of which is attached to the cam 10. The opposite end of this rod 38 carries a nut 39, and between the extension 37 and nut 39 is a spiral spring 40, surrounding the rod 38, and tending always to bring the cam 10 back into the inoperative position shown in Figure 1. 85

In ordinary normal operation, when a floor 90 is approached at which the elevator cage is to stop, the solenoid 32 is energized. This draws the magnetic core 24 to the left in Figure 1, revolving the gear 18, which pushes the toothed sleeve 12 to the right, and with it 95 the rod 11 and cam 10.

During the first part of this movement the oil or other liquid which occupies the oil chamber 14 and penetrates the tube 21 and core 24 is allowed to escape freely from the 100

left hand end of the tube 21 through the openings 35 and 36, although the ball valve 30 prevents the oil from passing through the bore 28.

5 In consequence the parts actuated by the solenoid move promptly and rapidly when started. In order to prevent slamming with consequent disagreeable noise and wear, the movement of the cam outward is considerably retarded at the end of the travel. This retardation results from passage of the opening 36 into the closed portion of the tube 21, as the core 24 moves to the left. When this occurs, oil can no longer pass through 10 the openings 35, 36, but must move slowly through the small space left under the core 24, as plainly shown in Figure 2.

To return the cam to the inoperative position shown in Figure 1, the solenoid is de- 20 energized; and the spring 40 on the rod 38 is free to draw the cam 10 to the left, thus reversing the movements of all the parts and restoring the position shown in the drawings.

During this return movement, the ball 25 valve 30 will be open and flow of oil will be free, thus leaving the action unretarded.

In case of failure of the solenoid to act through absence of electric current or other cause, it is desirable to provide emergency 30 operating means which can be actuated directly by the person in charge of the elevator. For this purpose I prefer to provide a two-armed pressure lever 41, 42 mounted revolu- 35 bly on a stub shaft 43 carried by the sup- porting casing. At the outer extremity of the longer of the two arms, 41, there is carried a stub shaft 44 which projects under or behind the cam 10 as shown in Figure 3. On the end of this shaft there is mounted a 40 revolvable roller 45, which can be pushed against the back of the cam 10 by tilting the lever 41, 42, on its pivotal support.

A tension rod 46 is pivotally attached to the outer extremity of the lever arm 42; and 45 a spring 47 having one end attached to the casing 13 and the other to the lever arm 41, tends always to retract the arms 41, 42, to the inoperative position shown in the drawings.

50 When it is desired to operate the cam by hand or foot, the arms 41, 42 are tilted by means of the tension rod 46, causing the roller 45 to press the cam 10 outward, carrying with it the rod 11 which slides freely within the sleeve 12, and compressing the spring 40. Upon releasing the tension on the rod 46, the spring 47 will return the lever arms 41, 42 and roller 45 to inoperative position, thus 55 permitting the spring 40 to bring the cam back to the idle position shown in Figure 1.

It will thus be seen that manual (or pedal) operation of the cam 10 can be accomplished without moving any of the mechanical elements employed for normal electro-magnetic operation. Manual operation is thus free

from any retarding action of the oil, and, moreover, if failure of normal operation has been due to sticking or breakage of any of said mechanical members, their disability cannot interfere with free manual operation. 70

Numerous changes may be made in the construction of this device without departing from the scope of my invention, which is not limited to the details herein shown and described. 75

What I claim is—

1. In a device of the class described, a movable cam, mechanism for normal operation thereof and means for emergency operation thereof adapted to operate the cam while said normal operating mechanism is at rest. 80

2. In a device of the class described a movable cam, mechanism for normal operation thereof comprising a carrying member, mounting means for the cam carried by said member and adapted to move freely thereon, and means for emergency operation of the cam independent of the normal operating means. 85

3. In a device of the class described, cam-operating mechanism comprising a sleeve adapted to reciprocate, a rod adapted to move in and out of said sleeve and a cam mounted on said rod. 90

4. Apparatus as in claim 3 in combination with a spring adapted to press the rod into the sleeve. 95

5. In a device of the class described, a cam mounted for reciprocating movement, a tiltable two-armed lever mounted near the same, a roller carried by one of said arms and adapted to press against the cam, and a spring tending to hold the roller away from the cam. 100

6. In a device of the class described, a supporting casing having an oil chamber, a solenoid, and a reciprocating magnetic core moving through said chamber and having an oil passage therein adapted to be closed when the core is between its two extremes of normal movement. 105

7. In a device of the class described, a supporting casing having an oil chamber, a solenoid, a reciprocating magnetic core moving through said chamber and having a longitudinal passage and a transverse passage connecting the same with the oil chamber, and an automatic valve in said longitudinal passage. 115

8. In a device of the class described, two reciprocating racks, a gear engaging both racks, a cam mounted on one of said racks and motivating means adapted to actuate the other rack. 120

9. Apparatus as in claim 8 wherein one of the racks has the form of a sleeve, and wherein in the cam is provided with a rod fitting said sleeve so as to be slidable therein. 125

10. Apparatus as in claim 8 wherein one of the racks is a magnetic core and wherein 130

a solenoid is provided adapted to act upon said core to reciprocate the same.

11. In a device of the class described, a supporting casing having an oil chamber, and a reciprocating rod moving through said chamber and having a longitudinal oil passage therein having a lateral opening adapted to be closed to check the movement of said rod when the rod is between its two extremes of normal movement and substantially before it reaches its limit of movement.

12. In a device of the class described, a cam and means for projecting said cam into and out of operative position, said means comprising a sliding part fixed to said cam, a second sliding part movable independently of said cam, and a motor for driving said second sliding part to project said cam.

13. In a device of the class described, a cam and means for projecting said cam into and out of operative position, said means comprising a sliding part fixed to said cam, a second sliding part movable independently of said cam, and a motor for driving said second sliding part to project said cam, said motor comprising a solenoid and a rod of magnetic material adapted to be reciprocated by the electro-magnet action of said solenoid; a gear connection between said rod and said second named sliding part, and a spring acting on said cam to retract the same, and also acting on said rod through said second named sliding part and gear connection, to retract the rod when said solenoid is de-energized.

14. In a device of the class described, a cam and means for projecting said cam into and out of operative position, said means comprising a sliding part fixed to said cam, a second sliding part movable independently of said cam, and a motor for driving said second sliding part to project said cam, and a second means for projecting said cam, said independent sliding movement between said cam and said second-named sliding part permitting the projection of said cam by said second means without actuation of said motor actuated means for projecting said cam.

In testimony whereof I have hereto affixed my signature on this 25th day of September, 1926.

H. W. SHONNARD.
